UNITED STATES PATENT OFFICE.

DAVID E. FISHER, OF KENTON, OHIO.

BRIDGE.

SPECIFICATION forming part of Letters Patent No. 665,317, dated January 1, 1901.

Application filed April 12, 1900. Serial No. 12,572. (No model.)

To all whom it may concern:

Be it known that I, DAVID E. FISHER, a citizen of the United States, residing at Kenton, in the county of Hardin and State of Ohio, have invented certain new and useful Improvements in Bridges, of which the following is a full, clear, and exact specification.

My invention consists in certain novel features of the construction of a bridge of the type known as "suspension-bridges."

In the annexed drawings, which fully illustrate my invention, Figure 1 is a side elevation of a bridge embodying the features of my present invention, and Fig. 2 is a similar view showing a slight modification.

In carrying out my invention I erect piers of masonry or other solid construction on the sides of the stream or gorge to be bridged, and upon these piers I anchor the beams or girders A, as clearly shown. Pivots secured to the inner ends of these beams or girders are the posts B, and extending between the beams across the space between the piers are the cables C. The floor of the bridge also extends between the ends of these beams A and is supported by the usual joists and chords. Rising from the lower chords, which support the floor at regular intervals, are the posts D, on which are the pulleys E. The upper ends of these posts are pivotally attached to the upper chord F, which has its ends pivotally connected to the upper ends of the posts B. Fulerumed on the pivotal connections of the upper chord F and the posts B are the short levers G, to the lower ends of which are secured the ends of the cable H, passing under the pulleys E. The upper ends of the levers G are pivoted to the upper ends of the braces I, extending to the outer ends of the beams A and anchored.

In the normal position of the parts the locking-levers G have their lower ends projecting away from the ends of the bridge. When a load is placed on the bridge, the strain is transmitted directly to the cable H and exerts an inward pull on the said levers, which tends to swing their lower ends inward. This movement of course causes an outward movement of the upper ends of the levers, which is resisted by the braces I, so that the entire strain put on the bridge is transmitted to and borne by the piers. Should an ex-

traordinary strain be placed on the bridge, the locking-levers might be brought beyond the vertical position, in which event they would tend to lift the posts to which they are fulcrumed; but this tendency would be positively resisted by the strut-braces between the several posts along the sides of the span.

My bridge is intended more especially for large streams, but its principle may be utilized in a bridge of any size.

The bridge commends itself by reason of its economical construction and the rapidity with which it can be built.

It may sometimes be desirable to have the beams A, which are the foundation of the bridge-approaches, inclined upward, as shown in Fig. 2. In this form of the bridge the locking-levers will be arranged with their upper ends projecting from the ends of the bridge. Under the strain of a load passing over this bridge the approaches will tend to assume a lower position, thereby drawing downward on the locking-levers and the braces, as will be readily understood. The braces, being anchored, will resist this downward movement, and consequently the levers will swing outward at their lower ends and draw upon the cable, so as to increase the tension of the same and impart additional rigidity to the structure. Should it be necessary to have one approach elevated more than the other, this arrangement of the levers (shown in Fig. 2) will be followed.

Single bolts are used throughout the structure, so that the several connections will be true pivotal connections and the necessary movements may readily occur. It will be readily understood that the resistance offered by the bridge is governed by the weight of the load passing over the span and that the heavier the load the more rigid will the bridge be. The cables are provided with turnbuckles, so as to be readily adjusted to an initial tension. The lower cables serve not only as a support for the floor, but also serve as a tie between the end beams or girders to prevent spreading of the lower portion of the bridge.

The weight or load is supported by the cable, so that the parts composing the top of the bridge may be light without affecting the rigidity of the structure. As the length of the bridge increases and the weight becomes

greater, it is necessary only to increase the size of the locking-levers and the parts connected directly therewith without using larger posts, &c. Consequently my bridge possesses 5 decided economical advantages.

Having thus described my invention, what I claim, and desire to secure by Letters Patent, is—

1. In a bridge, the combination of the end 10 posts and braces, locking-levers fulcrumed on the end posts and pivoted to the upper ends of the braces, and a cable secured to and extending between the ends of the levers.

2. The combination with the main structure, and the end braces, of a cable extending longitudinally of the main structure, and locking-levers fulcrumed on the main structure, pivoted to the end braces and acting on the cable.

20 3. In a bridge, the combination of the anchored end beams and braces, posts rising from the inner ends of the beams, locking-le-

vers fulcrumed on the upper ends of the said posts and having their upper ends pivoted to the upper ends of the braces, and cables extending between the ends of the locking-levers and secured to the lower ends of the same. 25

4. The combination of the end beams and braces, tie-cables and a floor connecting the end beams, posts rising from the end beams 30 and from the sides of the floor-span, the intermediate posts, pulleys on the posts, locking-levers fulcrumed on the upper ends of the end posts and pivoted to the end braces, and a cable secured to and extending between the 35 ends of the locking-levers and passing under the pulleys on the posts.

In testimony whereof I have signed this specification in the presence of two witnesses.

DAVID E. FISHER.
